UNITED STATES PATENT OFFICE

2,025,593

CIRCUIT CONTROLLING DEVICE

Lloyd E. King, Berwyn, Ill.

Original application January 9, 1931, Serial No. 507,587, now Patent No. 1,922,163. Divided and this application July 10, 1933, Serial No. 679,823

12 Claims. (Cl. 200—112)

My invention relates to an improved construction of circuit controlling devices responsive to abnormally high and abnormally low current flow or voltage in the controlling circuit, depending upon whether the control desired is to be determined by the amount of current flowing in the controlling circuit, or the voltage of the controlling circuit.

My invention broadly consists of a container which preferably is completely enclosed, in which there is a liquid conductor and a float which is responsive to magnetic action, together with an electro-magnetic winding which preferably is outside of the container, for controlling the position of the float in the liquid conductor, circuit terminals being provided in the container for closure or operation when the float reaches predetermined positions. More specifically, the structure referred to provides for the closure or operation of first electric contacts when the float reaches a predetermined high position and for the closure or operation of second electric contacts when the float reaches a predetermined low position. The closure or operation of the electric contacts is susceptible of use for controlling protective or other devices of various kinds as below referred to.

The present application is a divisional application of my co-pending United States application, Serial No. 507,587, filed January 9, 1931, now Patent No. 1,922,163 the latter application in turn being a divisional application of my earlier United States application Serial No. 653,200, filed July 23, 1928, which latter application has become Patent No. 1,792,310.

My invention will best be understood by reference to the accompanying drawing showing a preferred embodiment thereof in which

Fig. 1 is a vertical, sectional view of improved control mechanism responsive to abnormal electrical conditions in the supply conductors, this view being taken along the line 1—1 in Fig. 2, and

Fig. 2 is a horizontal sectional view of the parts shown in Fig. 1 taken along the line 2—2.

Similar numerals refer to similar parts throughout the several views.

In the drawing I illustrate my invention as embodied in a construction for effecting the protection of desired circuits and apparatus from abnormally high and abnormally low current flow or voltage, depending upon how the actuating coil of the device is wound and connected. In this construction the device is provided with an actuating coil 100 through which a tube 101 of insulating material, for example glass, extends, the coil being preferably movable axially of the tube, as illustrated by dotted lines, to adjust the action of the device. The tube 101 is provided with a lower terminal 102 and an upper terminal 103 of conducting material projecting through the ends of

the tube and in electrical connection with protecting caps 104 and 105 carried by the ends of the tube. The upper terminal 103 is branched on its inner end to form two contacts 103a and 103b, the former being axially disposed and the latter extending adjacent the inner side wall of the tube 101. The tube 101 contains a liquid conductor, for example mercury, as indicated at 106 and in the liquid conductor a float of magnetic material, for example iron, is disposed as indicated at 107. The float 107 is provided at its upper end with a cup 107a containing a liquid conductor, for example, mercury as indicated at 108. On its outer surface, the float 107 is grooved longitudinally as indicated at 107b, said grooves being lined with insulating material 109 so that the contact 103b may extend into one of said grooves without making electrical contact with the float 107. The float 107 carries at its lower end a perforated disc 110 secured in spaced relation to the end of the float by a central stud 111, said disc preferably having upwardly and downwardly projecting edge flanges as indicated. The parts of the device are so proportioned, and the level of the liquid conductor 106 is so taken, that under normal conditions of current flowing through the actuating winding 100, the contacts 103a and 103b will be out of contact with the liquid conductors 108 and 106 respectively. For this relation of the parts, with normal current flow through the winding 100, the float extends some distance above the upper end of the coil 100 and its lower end is within the lower end of said coil. If now the current flowing through the coil 100 decreases to a predetermined value lower than the normal value, the magnetic pull on the float 107 is decreased sufficiently to permit it to rise until the contact 103a makes electrical connection with the conductor 108, thus closing the control circuit extending from the terminals 102 and 103. On the other hand if the current flowing through the coil 100 is increased above its normal value until a predetermined higher value of current is reached, the magnetic pull on the float 107 is increased thus drawing it downwardly in the liquid conductor 106, for which condition the displaced liquid conductor 106 rises around the float until it makes electrical contact with the contact 103b, thus closing the control circuit extending from the terminals 102 and 103. It will be understood, that by changing the relation of the parts shown in Fig. 1, so the float 107 is normally below the coil 100, an abnormal increase of current flow will raise the float and close the control circuit through the contact 103a, and an abnormal decrease of current flow will permit the float to correspondingly sink and close the control circuit through the contact 103b.

The device just described may be constructed to actuate the control circuit for abnormally high and low current values in the protected circuit

5 by so winding the coil 100 that it may be included in series in said circuit and the same device may be employed to protect a circuit against abnormally low and abnormally high voltage by winding the coil 100 so that it may be connected between the conductors of the circuit to be protected and subjected to the voltage between said conductors.

10 It will be noted that the disc 110 extends nearly to the inner surface of the tube 101, as a result of which motion of the disc either upwardly or downwardly in the liquid conductor, is retarded and a time element of operation is introduced determined by the amount of clearance between the disc and the tube 101 and the size of the apertures through the disc. In this manner closure of the control circuit is prevented for either a momentary increase or a momentary decrease of current flow from its normal value, although 15 the same amount of change of flow might be sufficient, if maintained, to cause a closure of the control circuit.

20 While my improved circuit controlling devices above described may be adapted to a wide variety of purposes, they are particularly adapted for controlling protective devices which in turn control circuits that are desired to be protected, of the kinds and as described in my earlier applications above referred to. Circuit controlling devices of my present invention are particularly adapted for controlling the opening and closing of electric circuits in which relatively small amounts of current are flowing or are intended to flow and as to circuits of that kind, my circuit controlling devices may control the opening and closing of the desired circuits directly; where however the circuits to be ultimately protected are circuits in which relatively large currents are to flow, or the voltage of the circuits is considerable or both, it is desirable to directly control said circuits by secondary protective devices, for example of the kinds described in my other applications referred to, which secondary protective devices however may readily be controlled as to their operation, by the circuits directly controlled by the circuit controlling devices of my present invention.

25 While I have shown by invention in the particular embodiment above described, it will be understood that I do not limit myself to this exact construction as I may employ equivalents known to the art at the time of the filing of this application without departing from the scope of the appended claims.

30 What I claim is:

1. In a circuit closing device, the combination of a tubular container, liquid conductor in said container, a float of magnetic material in said conductor, a first terminal extending through said container into the lower part of said conductor, a second terminal extending through said container for connection with said liquid conductor by movement of said float from its mid-position in a first direction, a third terminal extending through said container for connection with said liquid conductor by movement of said float from its mid-position in a second direction, each of said second and said third terminals being out of contact with said liquid conductor when the other of said second and said third terminals is in contact with said liquid conductor and both of said second and said third terminals being out of contact with said liquid conductor for the mid-position of said float, and an electromagnetic winding for holding said float in its

mid-position for current flow of a first amount through said winding and for moving said float in said first and said second directions for decreased and increased current flow respectively through said winding. 5

2. In a circuit closing device, the combination of a tubular container, liquid conductor in said container, a float of magnetic material in said conductor, a first terminal extending through said container into the lower part of said conductor, a second terminal extending through said container for connection with said liquid conductor by movement of said float from its mid-position in a first direction, a third terminal extending through said container for connection with said liquid conductor by movement of said float from its mid-position in a second direction, each of said second and said third terminals being out of contact with said liquid conductor when the other of said second and said third terminals is in contact with said liquid conductor and both of said second and said third terminals being out of contact with said liquid conductor for the mid-position of said float, and an electromagnetic winding for holding said float in its 10 mid-position for current flow of a first amount through said winding and for moving said float in said first and said second directions for decreased and increased current flow respectively through said winding, said winding surrounding 15 said container and movable vertically thereon to secure a desired amount of magnetic action on said float.

3. In a circuit closing device, the combination of a tubular container, liquid conductor in said container, a float of magnetic material in said conductor, a first terminal extending through said container into the lower part of said conductor, a second terminal extending through said container for connection with said liquid conductor by movement of said float from its mid-position in a first direction, a third terminal extending through said container for connection with said liquid conductor by movement of said float from its mid-position in a second direction, each of said second and said third terminals being out of contact with said liquid conductor when the other of said second and said third terminals is in contact with said liquid conductor and both of said second and said third terminals being out of contact with said liquid conductor for the mid-position of said float, and an electromagnetic winding for holding said float in its 20 mid-position for current flow of a first amount through said winding, said winding surrounding 25 said container and movable vertically thereon to secure a desired amount of magnetic action on said float.

4. In a circuit closing device, the combination of a tubular container, liquid conductor in said container, a float of magnetic material in said conductor, a first terminal extending through said container into the lower part of said conductor, a second terminal extending through said container for connection with said liquid conductor by movement of said float from its mid-position in a first direction, a third terminal extending through said container for connection with said liquid conductor by movement of said float from its mid-position in a second direction, each of said second and said third terminals be- 70

5 ing out of contact with said liquid conductor when the other of said second and said third terminals is in contact with said liquid conductor and both of said second and said third terminals being out 10 of contact with said liquid conductor for the mid-position of said float, and an electromagnetic winding for holding said float in its mid-position for current flow of a first amount through said winding and for moving said float in said first 15 and said second directions for decreased and increased current flow respectively through said winding, said float carrying a cup containing liquid conductor for engaging one of said second and third terminals by upward movement of said float.

20 5. In a circuit controlling device, the combination of a container, liquid conductor in said container, a float in said liquid conductor, an electromagnetic winding for moving said float vertically in said liquid conductor, and two electric contacts for electrical contact with said liquid conductor by upward and downward movements respectively of said float each of said contacts being out of contact with said liquid conductor when the other of said contacts is in contact with said liquid conductor, said float carrying a cup containing liquid conductor for engaging one of said contacts by upward movement of said float.

25 6. In a circuit controlling device, the combination of a container, liquid conductor in said container, a float in said liquid conductor, an electromagnetic winding for moving said float vertically in said liquid conductor, and two electric contacts for electrical contact with said liquid conductor by upward and downward movements respectively of said float each of said contacts being out of contact with said liquid conductor when the other of said contacts is in contact with said liquid conductor, said float carrying a cup containing liquid conductor for engaging one of said contacts by upward movement of said float, said contacts being electrically connected with each other.

30 7. In a circuit controlling device, the combination of a vertically disposed tubular container, liquid conductor in said container, a cylindrical float in said container and having its outer surface adjacent the inner longitudinal surface of said container, electromagnetic means for moving said float, said float carrying at its upper end a cup containing liquid conductor, a first electric contact extending into said cup for engagement with the liquid conductor therein by upward movement of said float, said float having a longitudinal groove in its cylindrical surface, and a second electric contact extending into said groove for engagement with the liquid conductor in said container by downward movement of said float.

35 8. In a circuit controlling device, the combination of a vertically disposed tubular container, liquid conductor in said container, a cylindrical float in said container and having its outer surface adjacent the inner longitudinal surface of said container, electromagnetic means for moving said float, said float carrying at its upper end a cup containing liquid conductor, a first electric contact extending into said cup for engagement with the liquid conductor therein by upward movement of said float, said float having a longitudinal groove in its cylindrical surface, a second

40 electric contact extending into said groove for engagement with the liquid conductor in said container by downward movement of said float, and insulating material between the surface of said groove and said second contact.

45 9. In a circuit controlling device, the combination of a vertically disposed tubular container, liquid conductor in said container, a cylindrical float in said container and having its outer surface adjacent the inner longitudinal surface of said container, electromagnetic means for moving said float, said float carrying at its upper end a cup containing liquid conductor, a first electric contact extending into said cup for engagement with the liquid conductor therein by upward movement of said float, said float having a longitudinal groove in its cylindrical surface, a second electric contact extending into said groove for engagement with the liquid conductor in said container by downward movement of said float, and insulating material between the surface of said groove and said second contact, said contacts being electrically connected with each other.

50 10. In a circuit controlling device, the combination of a vertically disposed tubular container, liquid conductor in said container, a float in said container for vertical movement therein, electromagnetic means for moving said float, said float carrying at its upper end a cup containing liquid conductor, a first electric contact extending into said cup for engagement with the liquid conductor therein by upward movement of said float, there being a vertically extending clearance space between said float and said container, and a second electric contact extending into said clearance space for engagement with the liquid conductor in said container by downward movement of said float.

55 11. In a circuit controlling device, the combination of a vertically disposed tubular container, liquid conductor in said container, a float in said container for vertical movement therein, electromagnetic means for moving said float, said float carrying at its upper end a cup containing liquid conductor, a first electric contact extending into said cup for engagement with the liquid conductor therein by upward movement of said float, there being a vertically extending clearance space between said float and said container, and a second electric contact extending into said clearance space for engagement with the liquid conductor in said container by downward movement of said float, and insulating material between said float and said second contact.

60 12. In a circuit controlling device, the combination of a vertically disposed tubular container, liquid conductor in said container, a float in said container for vertical movement therein, electromagnetic means for moving said float, said float carrying at its upper end a cup containing liquid conductor, a first electric contact extending into said cup for engagement with the liquid conductor therein by upward movement of said float, there being a vertically extending clearance space between said float and said container, and a second electric contact extending into said clearance space for engagement with the liquid conductor in said container by downward movement of said float, and insulating material between said float and said second contact, said contacts being electrically connected with each other.

LLOYD E. KING.
